UNITED STATES PATENT OFFICE.

RICHARD BLACK, OF CANONSBURG, PENNSYLVANIA.

METALLIC RAILWAY-TIE.

SPECIFICATION forming part of Letters Patent No. 744,285, dated November 17, 1903.

Application filed April 29, 1903. Serial No. 154,785. (No model.)

To all whom it may concern:

Be it known that I, RICHARD BLACK, a citizen of the United States, residing at Canonsburg, in the county of Washington and State of Pennsylvania, have invented a new and useful Improvement in Metallic Railway-Ties, of which improvement the following is a specification.

My invention relates to the construction of railway-tracks or permanent ways; and it consists of an improved construction in a metallic tie which acts as the support of the rail and will be more fully set forth hereinafter.

In the accompanying drawings, forming a part of this specification, letters of reference designate like parts throughout the several views, in which—

Figure 1 is a top view of a section of a railway-track, showing the rails as affixed to my improved tie. Fig. 2 is a side view of one of my forms of railway-tie, showing a sectional view of the rails as seated therein. Fig. 3 is a perspective view of my improved tie.

In the drawings, the letter A represents the railway-rails, B the main body of the tie, and B' the base portion of the tie.

C is the outer brace of the tie, and D is the inner brace formed on the other end of my tie.

c is a recess or rail-chair formed in the tie near the outer brace portion, and d is a corresponding recess in the opposite end of the tie near the inner brace portion.

By referring to Fig. 3 the outlines of my tie will be seen.

These ties are to be laid in the usual way 35 on the road-bed, every other tie being reversed, so that the rails will be braced on the outside and inside alternately. After the rails have become firmly seated in the recesses or chairs provided for them the ties may then be 40 moved in such a manner as to bring the brace portions C and D firmly in contact with the web and base of the rail, and when properly adjusted the ties may be permanently embedded in the road-bed, and a firm and rigid 45 track will be had without the use of nuts, bolts, or fish-plates.

The cut-out portion d' at one end of the tie is for the admission of the rail to the chair d.

Having thus fully shown and described my 50 invention, what I claim as new, and desire to secure by Letters Patent, is—

In a reversible metallic railway-tie having the inner and outer brace portions C and D; the recesses or rail-chairs c and d; the base 55 portion B' and the cut-out d'; substantially as described and shown.

In testimony whereof I have hereunto signed my name in the presence of two subscribing witnesses.

RICHARD BLACK.

In presence of—

DANIEL DAY,
JAMES F. SPEER.
